UNITED STATES PATENT OFFICE.

GEORGE N. JAMESON, OF VINTON, IOWA.

DESIGN FOR A CLOTHES-POUNDER.

SPECIFICATION forming part of Design No. 34,099, dated February 19, 1901.

Application filed September 22, 1900. Serial No. 30,862. Term of patent 14 years.

To all whom it may concern:

Be it known that I, GEORGE N. JAMESON, a citizen of the United States, residing at Vinton, in the county of Benton and State of Iowa, have invented and produced a new and original Design for a Clothes-Pounder, of which the following is a specification, reference being had to the accompanying drawings, forming part thereof.

Figure 1 is a bottom plan view. Fig. 2 is a vertical central sectional view, and Fig. 3 is a perspective view.

The novel feature of my design consists in the cone-shaped hollow body A, provided with a concavo-convex bottom A², an open-ended straight tube B, fixed in the top of the body and in the center of the said fixed bottom,

and semicircular open-ended tubes C, fixed to the inside of the face of the hollow body and in openings in the bottom, and straight round tubes D, fixed in the central portion of the fixed bottom.

Having described my invention, what I claim as new, and desire to secure by Letters Patent, is—

The design for a clothes-pounder, as herein shown and described.

In testimony whereof I have signed my name to this specification in the presence of two subscribing witnesses.

GEORGE N. JAMESON.

Witnesses:

W. H. ANDERSON,
E. L. BROOKS.
